UNITED STATES PATENT OFFICE.

PEARL E. MILLER, OF FORT WORTH, TEXAS.

DESIGN FOR A FEEDING-CUP FOR RABBITS.

56,761.

Specification for Design.

Patented Dec. 14, 1920

Application filed April 28, 1919. Serial No. 293,362. Term of patent 3½ years.

To all whom it may concern:

Be it known that I, PEARL E. MILLER, a citizen of the United States, residing at Fort Worth, in the county of Tarrant and State of Texas, have invented a new, original, and ornamental Design for a Feeding-Cup for Rabbits, of which the following is a specification, reference being had to

the accompanying drawing, forming part thereof.

The figure is a perspective view of a feeding cup for rabbits, showing my new design.

I claim:

The ornamental design for a feeding cup for rabbits as shown.

PEARL E. MILLER.
